UNITED STATES PATENT OFFICE.

PATRICK J. HARE, OF NEW YORK, N. Y.

APPARATUS FOR EXTRACTING LIQUIDS FROM GARBAGE OR OFFAL.

1,238,289.

Specification of Letters Patent.

Patented Aug. 28, 1917.

Application filed November 12, 1915, Serial No. 61,028. Renewed January 29, 1917. Serial No. 145,309.

To all whom it may concern:

Be it known that I, PATRICK J. HARE, a citizen of the United States, and residing at New York, in the county of New York and State of New York, have invented certain new and useful Improvements in Apparatus for Extracting Liquids from Garbage or Offal, of which the following is a specification, such as will enable those skilled in the art to which it appertains to make and use the same.

This invention relates to apparatus for extracting or separating liquids from garbage or offal so that said garbage or offal may be treated in the usual manner for any purpose, and the object of the invention is to provide an apparatus of the class specified which is simple in construction, convenient of and effective in operation, and which is also comparatively inexpensive, and by means of which the said operation of separating liquids from garbage or offal may be quickly, easily and effectively performed; and with this and other objects in view the invention consists in a machine or apparatus of the class specified, constructed and operating as hereinafter described and claimed.

The invention is fully disclosed in the following specification, of which the accompanying drawing forms a part, in which the separate parts of my improvement are designated by suitable reference characters in each of the views, and in which:—

Figure 1 is a sectional side view of my complete apparatus with part of the construction broken away;

Fig. 2 a sectional plan view on the line 2—2 of Fig. 1 with part of the construction broken away; and,

Fig. 3 a transverse sectional view on the line 3—3 of Fig. 1 and looking backward and on an enlarged scale.

In the practice of my invention, as shown in the drawing, I provide a strong and substantial main frame consisting of two similar side members *a* composed of any suitable material and connected, in the construction shown, by two transverse bolts, bars or rods *a*² at the opposite ends and near the bottom thereof and by transverse bars *a*³ at the top thereof, but the side members *a* of

the main frame may be formed and connected in any desired manner.

The main frame, or the side members thereof, are provided centrally of the top 55 thereof with a raised portion *a*⁴ in which are mounted two rollers *b*, and said raised portion *a*⁴ of the frame, or the side members thereof, are provided with vertically arranged slots or openings *b*² over which are 60 secured yoke-shaped brackets *b*³, and mounted in the slots or openings *b*² are vertically movable bearing blocks *b*⁴, and the rollers *b* are provided with reduced end portions *b*⁵ through which are passed shaft *b*⁶, the ends 65 of which pass into the bearing blocks *b*⁴.

Mounted in the yoke-shaped brackets *b*³ are threaded sleeves *b*⁷ provided at their upper ends with nut-shaped heads *b*⁸, and at their lower ends with blocks *b*⁹, and 70 passed downwardly through the threaded sleeves *b*⁷ and screwed into the bearing blocks *b*⁴ are rods *c* provided at their upper ends with handle members *c*², and between the blocks *b*⁹ and the bearing blocks *b*⁴ are 75 spiral springs *c*³ through which the rods *c* pass, and by means of this construction the bearing blocks *b*⁴ and the rollers *b* may be raised and lowered, or adjusted vertically when desired, and the springs *c*³ normally 80 serve to depress the rollers *b* as will be understood. The blocks *b*⁹ are rotatable with the sleeves *b*⁷, and by turning said sleeves the tension of the springs *c*³ may be regulated.

Mounted directly under the rollers *b* are cylindrical drums *d* which are hollow in form and which are provided with end members *d*² having hub portions *d*³ and shafts *d*⁴ are passed through said drums and 90 through the side portions of the main frame, and the end portions *d*² of said drums are provided with projecting flanges *d*⁵.

The body of the front drum *d* is provided with circumferential grooves *d*⁶, in the form 95 of construction shown, and longitudinal grooves *d*⁷ which intersect the grooves *d*⁶, and at the points of intersection of these grooves, said drum is provided with apertures *d*⁸, and the body of the rear drum *d* 100 is provided, in the form of construction shown, with longitudinal slots or openings

d^0 which are preferably arranged as shown in Fig. 2 so that the longitudinal slots or openings in one line will overlap those in another.

- 5 The shafts d^4 of the drums d are provided at the right side of the machine with gears e and at the left side of the machine with worm gears e^2 , and the gears at the right side of the machine mesh with similar gears e^3 mounted on the shafts b^6 which extend through the bearing blocks b^4 at said side of the machine.

On the outer side of the left side of the machine is mounted a worm gear shaft f having worms f^2 which mesh with the worm gears e^2 , and the shaft f is provided centrally with a ratchet f^3 , and the left side frame member a is provided between the rollers b with projecting arms f^4 in which is mounted 20 a vertically movable rod f^5 provided at its lower end with a pawl f^6 operated in one direction by a spring f^7 to engage the ratchet f^3 , and said rod f^5 is provided between the arms f^4 with a collar f^8 between 25 which and the lower arm f^4 is placed a spiral spring f^9 which normally serves to force the rod f^5 upwardly.

The rod f^5 is provided at its upper end with a yoke g in which is pivoted an anti-friction roller g^2 , and mounted on the top of the main frame and centrally of the raised portion a^4 thereof is a transverse shaft g^3 , the ends of which project at both sides of the main frame, and at the left side 35 of the apparatus, said shaft is provided with a cam g^4 which operates in connection with the roller g^2 to move the rod f^5 downwardly at each revolution of said shaft g^3 .

The shaft g^3 is provided at the right side 40 of the machine with a pulley g^5 , and mounted transversely of the rear end portion of the main frame and in the top thereof is a shaft g^6 which carries a cylindrical brush g^7 , and the shaft g^6 is provided at the right 45 side of the machine with a pulley g^8 , and mounted on the pulleys g^5 and g^8 is a belt h .

The shaft g^6 is vertically adjustable, and this adjustment is effected by screws h^2 at the opposite ends thereof and any suitable 50 construction to produce this result may be employed. The shaft g^3 is also the main drive shaft of the machine and is provided at the right side thereof with a pulley h^3 , and said shaft and the machine may be 55 driven by a belt h^4 operated by any suitable power device.

Mounted in the front and rear end portions of the main frame are belt conveyer rollers i , and in the bottom portion of the 60 main frame and slightly at the front and rear of the drums d are smaller belt conveyer guide rollers i^2 , and mounted on the rollers i and passing between the rollers b and drums d and beneath the rollers i^2 is

an endless or belt conveyer i^3 , preferably 65 composed of strong heavy fabric material, and beneath the drums d and between the rollers i^2 in the construction shown is placed a pan j , the bottom of which is preferably inclined downwardly in the direction of the 70 left side of the machine, and this pan is made in the form of a drawer, and may be inserted into position by passing it through the left side of the main frame, as shown in Figs. 1 and 3, and the front of said pan 75 is provided with handles j^2 and with a flexible discharge pipe j^3 .

Mounted in front of the machine and provided, in the construction shown, with an independent support k is a feeder m , consisting of a main outer barrel or casing m^2 and a supplemental inner barrel or casing m^3 between which is an annular chamber m^4 .

The supplemental inner barrel or casing m^3 projects through the front end of the 85 main barrel or casing m^2 and is provided at the front thereof with a hopper m^5 , and mounted centrally in said supplemental inner casing m^3 is a tubular shaft m^6 provided with perforations m^7 and a spiral conveyer web m^8 , and the front end of the shaft m^6 projects and is provided with a pulley m^9 on which is mounted a belt n whereby said shaft may be turned, and the casing m^2 is provided with a hot water or steam inlet 90 pipe n^2 , and a discharge pipe n^3 , and a hot water or steam pipe n^4 extends into the front end of the shaft m^6 , and said pipes are provided with valves n^5 .

The back or rear end of the inner 100 conveyer casing m^3 is provided with a discharge chute o having a discharge opening o^2 , the dimensions of which may be regulated by an adjustable top plate or cover o^3 .

With the foregoing description, the operation will be readily understood in view of the following statement. The garbage or offal is fed into the feeder m through the hopper m^5 and the conveyer shaft m^6 being set in operation, the said garbage or offal 105 is fed through the feeder and discharged onto the belt i^3 and is carried by said belt between the rollers b and the drums d . During this operation hot water or steam is admitted through the pipes n^2 and n^4 , and this aids in separating the liquids from the garbage or offal, and especially is this true when said garbage or offal contains an amount of grease. In the passage of the 110 garbage or offal between the rollers b and drums d , the liquids contained in said garbage or offal are extracted or separated therefrom and pass through the drums d , or the apertures and slots d^8 and d^9 therein and fall into the pan j , and may be drawn 115 off from said pan through the pipe j^3 , and said pan may be removed and cleaned whenever desired.

The function of the brush g^7 which is cylindrical in form is to clean the conveyer belt i^3 , or remove therefrom the garbage or offal after liquids have been extracted therefrom, and in the above described operation, a part of the liquids extracted from the garbage or offal will pass downwardly around the drums d and, as will be seen, the operation of the rollers b and drums d is an intermittent operation, this result being effected by means of the rod f^5 , the ratchet f^2 on the shaft f , the pawl f^6 and the cam g^4 on the shaft g^3 , and this operation also facilitates the extraction of the liquids from the garbage or offal by reason of the fact that the said garbage or offal remains longer under compression as it passes between the rollers b and drums d , but my invention is not limited to this intermittent motion of the parts referred to, nor to the exact details of the construction herein shown and described, and the feeder m may be mounted in connection with the main frame, if desired, and other changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. In an apparatus of the class described, a main frame, a drum mounted therein, a roller mounted over said drum, an endless belt conveyer mounted to pass between said roller and said drum, and a feeder mounted in front of said roller and said drum and adapted to discharge material onto the conveyer, said drum being hollow and cylindrical in form and the body thereof being provided with apertures, said drum being also provided on its face with circumferential and longitudinal grooves which communicate with said apertures.

2. In an apparatus of the class described, a main frame, rollers mounted in the top portion, drums mounted beneath said rollers, an endless belt conveyer mounted to pass between said rollers and said drums, and means for giving said rollers, drums and conveyer intermittent movement.

3. In an apparatus of the class described, a main frame, rollers mounted in the top portion thereof, drums mounted beneath said rollers, an endless belt conveyer mounted to pass between said rollers and said drums, means for giving said rollers, drums and conveyer an intermittent movement, means for cleaning said conveyer after it passes between said rollers and said drums, and means for feeding material onto said conveyer in front of said rollers and said drums.

4. In an apparatus of the class described,

a main frame, rollers mounted in the top portion thereof, drums mounted beneath said rollers, an endless belt conveyer mounted to pass between said rollers and said drums, means for giving said rollers, drums and conveyer an intermittent movement, said drums being provided on their perimeter with grooves and apertures, and a feeder mounted in front of said rollers and drums and adapted to discharge material onto the conveyer.

5. In an apparatus of the class described, a main frame, rollers mounted in the top portion thereof, drums mounted beneath said rollers, an endless belt conveyer mounted to pass between said rollers and said drums, means for giving said rollers, drums and conveyer an intermittent movement, said drums being provided on their perimeter with grooves and apertures, a feeder mounted in front of said rollers and said drums and adapted to discharge material onto the conveyer, and means for adjusting the pressure of said rollers and said drums.

6. In an apparatus of the class described, a main frame, a drum mounted therein, a roller mounted over said drum, said roller being provided at its ends with trunnions mounted in blocks which are vertically movable in slots in the main frame, tension devices mounted in said slots above said blocks, means for adjusting said tension devices into different positions to increase or decrease the pressure of said roller on said drum, an endless belt conveyer mounted to pass between said roller and said drum, and means for giving said roller, drum and conveyer an intermittent movement.

7. In an apparatus of the class described, a main frame, a drum mounted therein, a roller mounted over said drum, tension devices mounted in the main frame and in connection with said roller, means for adjusting said tension devices into different positions to increase or decrease the pressure of said roller on said drum, an endless belt conveyer mounted to pass between said roller and said drum, means for giving said roller, drum and conveyer an intermittent movement, a feeder mounted in front of said roller and said drum and adapted to discharge material onto the conveyer, and a detachable receptacle mounted beneath said drum and adapted to receive the oil or liquid pressed from said material as it passes beneath said roller and drum.

8. In an apparatus of the class described, a main frame, rollers mounted in the top portion thereof, drums mounted beneath said rollers, an endless belt conveyer mounted to pass between said rollers and said drums, means for giving said rollers, drums and conveyer an intermittent movement, said drums being provided on their perimeter

with grooves and apertures, a feeder mounted in front of said rollers and drums and adapted to discharge material onto the conveyer, and means adjustably mounted in the main frame for removing said material from said conveyer.

In testimony that I claim the foregoing as

my invention I have signed my name in presence of the subscribing witnesses this 9th day of November 1915.

PATRICK J. HARE.
